DESIGN FOR A SWIVEL CHAIR

Charles B. Fletcher and Peter J. Nordby,
Marietta, Ohio, assignors to Marietta Chair
Company, Marietta, Ohio, a corporation of
Ohio

Application October 16, 1942, Serial No. 108,538

Term of patent 14 years

To all whom it may concern:

Be it known that we, Charles B. Fletcher and Peter J. Nordby, citizens of the United States, residing at Marietta, in the county of Washington and State of Ohio, have invented a new, original, and ornamental Design for a Swivel Chair, of which the following is a specification, reference being had to the accompanying drawing, forming part thereof.

Fig. 1 is a side elevational view of a swivel chair, showing our design; and

Fig. 2 is a perspective view thereof, as seen when viewed from the bottom thereof.

The dominant feature of our design resides in the portion shown in full lines in the drawing.

We claim:

The ornamental design for a swivel chair, as shown and described.

CHARLES B. FLETCHER.
PETER J. NORDBY.
